UNITED STATES PATENT OFFICE.

CHARLES A. LITTLEFIELD, OF FALL RIVER, MASSACHUSETTS, ASSIGNOR TO
ELIAS A. TUTTLE, OF SAME PLACE.

LOOM.

SPECIFICATION forming part of Letters Patent No. 414,864, dated November 12, 1889.

Application filed February 25, 1889. Serial No. 301,127. (No model.)

To all whom it may concern:

Be it known that I, CHARLES A. LITTLEFIELD, a citizen of the United States, residing at Fall River, in the county of Bristol and 5 State of Massachusetts, have invented certain new and useful Improvements in Looms, of which the following is a specification.

In the accompanying drawings, Figure 1 is a front view of part of a loom with my invention applied thereto. Fig. 2 is a partial plan view thereof. Fig. 3 is a partial side view thereof. Fig. 4 is an elevation showing details. Fig. 5 is a view in vertical section showing details; and Figs. 6, 7, and 8 are respectively a partial side view, partial front view, and partial side view, showing modifications of the pattern devices for determining the positions of the shuttle-boxes.

The shuttle-box C slides horizontally upon 20 the upper surface of the race-beam A'' and contains two cells. At the inner end it has an overhanging lip c¹², fitted to a guideway, c¹³, formed in the throat-piece C' and retained in place therein by an overlying confining-plate 25 q, held to the throat-piece by screws q' q''. At the outer end the shuttle-box C slides upon a frame C'', secured to the race-beam and provided with ears c³, through which pass screws g g, which by engagement with the projection 30 q⁵ on the end of the shuttle-box serve to limit the lateral movement in each direction of the shuttle-box. Plates g' g'', applied to or forming part of frame C'', project across the upper side of the shuttle-box, with a space or 35 opening between their adjacent ends to permit the movement of the picker-stick, and constitute guides serving to prevent that shuttle which for the time being is out of action from being moved endwise into improper position. 40 To ears e e on the rear side of the shuttle-box are pivoted the front ends of links e' e', the other ends of which are pivoted to arms e'' e''', fast on the shaft e², the said shaft being journaled in brackets d d', secured to the race-beam A'', and being bent at or near its middle portion, as shown, to avoid coming in contact in its movement rearward with the hand-wheel D''' upon the crank-shaft A²¹. An arm e⁴, fast upon the shaft e², or made integral 45 with arm e'', has jointed to it the upper end of rod e³, the lower end of which is jointed to

the horizontal rearwardly-extending arm of a bell-crank H, pivoted to the shoe B''', secured to the lay rock-shaft B', as shown in Fig. 1. To the vertically-extending arm of 55 bell-crank H is jointed one end of rod H', the opposite end of which is jointed to the vertically-depending arm of a T-shaped lever or casting H'', pivoted on a stud H² upon the loom-side. The oppositely-extending horizontal arms of this lever H'' have passed therethrough at the ends the rods M' M', upon which, below the arms of the lever H'', are spiral springs h and nuts h'. The upper ends of rods M' M' are connected to 60 the levers M M, which are pivoted upon a rod m'', passing through the loom-side and a bracket L, made fast to the outer end of the long stud or arbor L⁴, which projects from the loom-side. These levers M M are provided 65 with friction-rollers bearing against the periphery of a pattern-wheel M⁴, mounted on stud L⁴ and provided with lugs l, secured to the same by screws l', and adapted to raise the levers alternately, the projections being 70 of sufficient length to hold each lever raised as long as may be required by the exigencies 75 of the pattern to be produced in the cloth to be woven. At the side of pattern-wheel M⁴ and fast therewith is a notched stop-wheel 80 L⁶, with which engages the tooth of a locking-lever m, held against the periphery of said stop-wheel by a spring r. A ratchet-wheel L' is made fast to the stop-wheel and pattern-wheel and is engaged by the pawl n', 85 pivoted on the arm n, mounted to oscillate upon stud L⁴, and connected by rod n'' to crank-pin f, rotating with the crank-shaft A². To the bracket L is also pivoted at one end the controlling-lever h², which, in the construction 90 represented in Fig. 3, has jointed to the same one end of rod h''', the opposite end of which is connected to crank-arm h'', carried by the cam-shaft A³, the latter being rotated from the crank-shaft at one-half the 95 rate of speed of the latter by the gears D'' D', as usual.

By the devices and construction so far described, as the pattern-wheel is rotated, the projections l thereon alternately raise the levers M M, which, through the rods M' M', lever or casting H'', rod H', bell-crank H, rod e³,

arm e^4 , shaft e^2 , arms $e'' e'''$, and links $e' e'$, move the shuttle-box backward and forward upon the upper surface of the race-beam, and thus alternately present the two shuttles 5 therein to the action of the picker-stick. Upon the elevation of either lever M the spring h upon the corresponding rod M' becomes compressed and serves during the movements of the lay to hold the projection q^5 10 in firm contact with one of the set-screws g . The crank-pin f , making one revolution at each pick of the loom, would move the pattern-wheel at each pick, were it not for the controlling-lever h^2 , which, being raised at 15 one pick and lowered at the next, by engagement with pin h^3 on pawl n' , lifts said pawl from engagement with wheel L' , and thus prevents the pattern-wheel from being moved and the shuttle-box shifted until after the 20 shuttle has been returned to the movable shuttle-box from the single-box side of the loom.

I prefer in some instances to employ in connection with lever h^2 pattern-controlling devices for holding the same in elevated position when desired to thus occasion dwells of greater or less duration in the rotation of the pattern wheel or wheels formed or provided with the cam-surfaces which determine the 25 position of levers M . Thus, in the construction shown in Figs. 6 and 7, in which the pattern-wheel is replaced by simple oppositely-placed cam disks or wheels $O^2 O^2$ the lever h^2 is not jointed to rod h''' , but rests in 30 the crutch o'' , applied to the side thereof, and said lever h^2 is jointed to one end of a rod o^3 , the opposite end of which is jointed to a lever o^2 , resting at O''' against the periphery of a controlling pattern-wheel O , provided 35 with pins p . These pins acting against the lever o^2 serve to hold lever h^2 elevated when desired and keep the pawl n' out of engagement with the ratchet-wheel L' , so as to produce an extended dwell in the rotation of the 40 disks or wheels $O^2 O^2$. Wheel O is rotated by ratchet-wheel O'' , connected therewith, pawl o''' , and bell-crank lever O' , jointed to the upper end of rod h''' . In some instances the pawl o''' may be placed under the control of 45 the third pattern-wheel, as P in Fig. 8, in which figure the pawl o''' has jointed thereto one end of a rod o^5 , which is connected at its other end to a lever P' , resting against the surface of the wheel P , the latter being rotated by means of ratchet-wheel P^2 , pawl s , and bell-crank lever s^9 , also jointed to the upper end of rod h''' .

Brackets c'' depend from the shuttle-box at front and rear of the race-beam. To these 50 brackets are pivoted levers b^3 , the lower ends of which are turned toward each other, as shown in Fig. 5, and are beveled, as represented. The protector-shaft a^5 , mounted in bearings on the lay and carrying dagger y , 55 engaging the frog or bunter y' on the loom-frame, as usual, carries an arm c^6 at one end,

which arm is provided with a stud c^5 , adapted to bear upon the upper side of the horizontal arm of one or the other of the levers b^3 , according as the shuttle-box is in its forward or 70 rearward position. The upper ends of the levers $b^3 b^3$ rest against the binders $c c$ of the shuttle-box, and the levers are moved thereby on the entrance of the shuttles into the box, their horizontal arms acting upon stud c^5 to 75 rock the protector-shaft and lift the dagger out of position for engagement with the frog F' .

g^4 is a check against which the picker-stick rests when at the outward extreme of its 80 movement. This check g^4 is a curved arm mounted on a shaft g^7 , passing through depending lugs secured to the race-beam and having at one end thereof the arm g^5 , to which is connected the upper end of rod g''' , the lower end of which is pivoted to an arm projecting from a lever J , pivoted on the foot-motion stock B''' . The upper end of the lever J is connected by rod J' to the end of the downwardly-projecting arm J'' , mounted on 90 the shaft J''' , which latter is journaled in brackets $k k$, secured to the loom-side and provided with an arm J^{1v} , projecting laterally beneath the adjacent picking-cam a' , it carrying a picking-bowl a''' . A spring J^9 draws 95 the arm J^{1v} upwardly into contact with the cam a' and normally holds the check g^4 in position to arrest the picker-stick in its outward movement at a point where it will arrest the shuttle, with its point just inside the 100 guide-plates $g' g''$. Just before the time at which a change is to be made in the position of the shuttle-box the picking-cam a' depresses arm J^{1v} , rocking shaft J''' , and turns lever J , so that its upper extremity pushes 105 against the picker-stick a^3 , carrying its upper end outward. The picker-sticks (only one stick is shown) a^3 are operated by means of shaft A^3 , cams $a a'$, bowls $a'' a'''$, arms $a^8 a^8$, shafts $a^9 a^9$, arms $b' b'$, and straps b , all as 110 shown in Fig. 1, being held in their retracted or outer position by means of springs f'' , as usual.

Having thus described my invention, I claim—

1. The combination, with the lay and the horizontally-sliding shuttle-box, of the shaft e^2 , connected with the shuttle-box, an arm on 115 said shaft, rod e^3 , bell-crank H , rod H' , lever H'' , and means for oscillating said lever H'' , substantially as described.

2. The combination, with the lay and the horizontally-sliding shuttle-box, of the shaft e^2 , connected with the shuttle-box, an arm on 120 said shaft, rod e^3 , bell-crank H , rod H' , lever H'' , rods M' , levers $M M$, and a pattern surface or surfaces for alternately raising said levers, substantially as described.

3. The combination, with the lay and the horizontally-sliding shuttle-box, of shaft e^2 , 125 connected with the shuttle-box, rod e^3 , bell-crank H , rod H' , lever H'' , rods $M' M'$, springs 130

h h, levers *M M*, and a pattern surface or surfaces for alternately raising said levers, substantially as described.

4. The combination, with the pattern-wheel, 5 its ratchet-wheel and pawl, the crank-shaft, and means for actuating said pawl at every revolution of the crank-shaft, of lever *h*², rod *h*³, crank *h*², and the cam-shaft, whereby the pawl is lifted out of the teeth of the 10 ratchet at every alternate revolution of the crank-shaft, substantially as described.

5. The combination, with the pattern-wheel, its ratchet and pawl, the crank-shaft, and means for actuating said pawl at every revolution of the crank-shaft, of rod *h*³, crank *h*², the cam-shaft, lever *h*², rod *o*³, lever *o*², a controlling pattern-surface, and means for actuating said pattern-surface, substantially as described.

20 6. The combination, with the pattern-wheel, its ratchet and pawl, the crank-shaft, and means for actuating the pawl to move the ratchet and pattern-wheel at every revolution of the crank-shaft, of lever *h*², rod *h*³, 25 crank *h*², the cam-shaft, bell-crank *O*', pawl *o*³', ratchet *O*'', pattern-wheel *O*, lever *o*², and rod *o*³, substantially as described.

7. The combination, with the pattern-wheel, its ratchet and pawl, the crank-shaft, and 30 means for actuating the pawl from the crank-

shaft, of lever *h*², rod *h*³', crank *h*², the cam-shaft, two supplementary pattern-wheels, the first thereof for controlling the position of lever *h*² and the second for controlling the engagement of the actuating-pawl with the 35 ratchet of said first supplementary pattern-wheel, the actuating-pawls for said ratchets, the bell-cranks connected with the rod *h*³', the rods *o*³ *o*⁴, and the levers *o*² *P*', substantially as described.

40 8. The combination, with the protector-shaft and its arm, having the stud, of the sliding shuttle-box, its binders, the brackets carried by said box, and the levers pivoted to said brackets, bearing at their upper ends 45 against the shuttle-binders and adapted for engagement with said arm of the protector-shaft, substantially as described.

9. The combination, with the picker-stick, of check *g*⁴, arm *g*⁵, rod *g*³', lever *J*, adapted 50 to bear at its upper end against the picker-stick, shaft *J*³ and its arms, rod *J*', and cam *a*', substantially as described.

In testimony whereof I have hereunto signed my name in the presence of two witnesses.

CHARLES A. LITTLEFIELD.
